[57] ABSTRACT

A hair stylists accessory tray is comprised of a base receptacle having a V shaped bottom and upstanding peripheral walls, the receptacle being adjustably supported on a mobile stand. A second receptacle is disposed above the base receptacle and has smaller dimensions length and width wise to provide manual access to the base receptacle at its sides. The upper receptacle has sloping sides merging into a horizontal bottom. Both upper and base receptacles are positioned in such fashion as to hold specific sizes of curling rollers, hair pins, clamps, etc., used in hairdressing in an orderly fashion readily accessible to an operator. Preferably the unit is formed of one piece of plastic or similar material by molding.

HAIR STYLISTS ACCESSORY TRAY OF THE LIKE

The invention deals with hair stylists accessory trays. In particular it is designed to provide a hair stylist with receptacle means specifically configured to place hair styling implements in an orderly fashion at his or her immediate disposal.

Hair stylist or beauty operator's trays are not new, per se. Such units as are available presently are trays mounted on a wheeled stand and comprising a plurality of compartments of generally box shape, i.e., rectangular with vertical side walls and horizontal bottoms. These trays, while convenient, are still not satisfactory in that the items accumulate in the various compartments in a jumbled mess and also spill from one compartment to another. In addition items of different sizes become intermingled with the result that the user must spend time to painstakingly unravel the general mess when selecting various items for use.

Time, for the hair stylist, is valuable because, not only must the stylist accommodate the most customers possible on a day to day basis, but even more important, some hair treatments are of a nature as to require rapid action by the stylist. Thus, the stylist must have available at a moments notice various and sundry accessories such as pins, curlers, clamps, rollers of multiple sizes, in order to affect the desired styling techniques.

The present invention, then, has for its principle object, among others not specifically set forth but inherent therein, the provision of a tray for storage of hair stylist's accessories or implements in an orderly manner with various sizes properly separated and readily available at the convenience of the stylist.

The tray is comprised of a pair of tiered receptacles including a rectangular base receptacle, having a V-shaped bottom and vertical peripheral side walls, a plurality of dividing walls for compartmentalizing the base receptacle into a plurality of compartments, said dividing walls being parallel to each other and transverse to the apex of the V-shaped bottom and spaced apart at equal distances from each other except at the center of the base receptacle; an upper tray centrally disposed, of rectangular configuration disposed over the base receptacle, said upper tray being of smaller width but of equal length as the base receptacle and having side walls inclined toward its center and interconnected by a horizontal bottom, dividing walls in said upper receptacle for compartmentalizing same into a plurality of compartments said dividing walls forming certain compartments of rectangular form adjacent the ends of the upper tray and stand means supporting said base tray for pivotal movement about a vertical axis and means for adjusting the receptacles vertically on said stand means.

Having broadly described the invention, a more detailed description follows with reference therein being made to the accompanying drawings wherein:

FIG. 1 is an end perspective view of a hair stylists tray according to the invention;

FIG. 2 is an enlarged perspective view of the tray shown in FIG. 1 showing in greater detail the manner in which the tray is compartmentalized while;

FIG. 3 is a side sectional view taken along the line 3-3 of FIG. 2 and also showing in outline form the manner in which hair curling rollers are deposited in the base receptacle.

As shown in FIG. 1 the complete hair stylist's tray includes a stand 1 of tripod configuration having three legs 3 terminating in conventional caster wheels 5. The legs 3 merge into a single, vertical, tubular column 7 upon which the tray 10 is mounted for rotation and vertical adjustment as will subsequently be described.

Further consideration of FIG. 1 will reveal that the tray 10 is of one piece construction in the preferred form having been manufactured of a moldable plastic by known techniques. Of course, as economics of manufacture and material costs are brought into consideration it might be advisable to mold the base receptacle and upper receptacle separately and thereafter to bond the units integrally together by any suitable adhesive or bonding process depending on the materials used.

Turning now to FIGS. 2 and 3, it may be seen that the lower receptacle 10 has an inverted V-shaped bottom 11 and vertical marginal or peripheral side and end walls 13, 15, 17 and 19 respectively. The apex 21 of the inverted, V-shaped bottom is disposed lengthwise of the tray and parallels the longer sides 13, 15 of the receptacle midway therebetween.

The interior of base receptacle 11 is also provided with dividers, said dividers 23 being spaced apart equally and paralleling the shorter sides 17 and 19 thereof.

The preferable dimensions for the receptacle are as follows:

Length — 24 inches

Width — 17 inches

Height of walls at corners — 2½ inches

Depth at apex of inverted V-shaped Bottom — 4½ inches

Spacing between dividers — 3¼ inches (except at center — 4 inches)

As also shown the bottom 11 of the base receptacle is provided with a centrally located aperture 21 through which may be inserted the upper end of vertical standard 7 of the stand 1.

Disposed above the base receptacle with its sides and ends aligned with the side and end walls 13, 15, 17 and 19 of the former is a secondary or, as defined hereinafter, a tiered receptacle 30. This receptacle is comprised of a horizontal bottom 31 a pair of divergently sloped side walls 33 and 35 and a pair of parallel vertical end walls 37 and 39. The end walls are aligned with or may be an upward extension of the end walls 17 and 19 of the base receptacle.

The tiered receptacle 30 is also compartmentalized by the use of a plurality of dividers paralleling the end walls 37 and 39. These dividers, four in number, are symmetrically arranged with one pair 41, 41' being spaced approximately 3½ inches from each end wall and the second pair 43, 43' being spaced a distance of 6½ inches from each of the first mentioned dividers 41, 41'.

The compartments formed between end walls 39 and 37 and dividers 41, 41' are further sub-divided by a number of parallel dividing walls disposed parallel to the longer axis of the tiered receptacle 30. Between divider 41 and end wall 39 are two subdividers 47, 47' which form therewith the pockets, two with sloping bottoms.

Between side wall 37 and divider 41' there are provided three equally spaced sub-dividers 49, 49' and

49" all parallel to each other and also to the longer axis of the base receptacle so that four pockets, two with sloping bottoms; two with horizontal bottoms are defined adjacent wall 37, while three pockets; two with sloping bottoms are formed adjacent side wall 39.

The precise central area of the tiered receptacle between dividers 43, 43' is also subdivided by a pair of parallel sub-dividing walls 51, 53. A horizontal bottom 55 is provided for the pocket area so formed. The bottom 55 and as well the bottom 31 of the tiered receptacle are both provided with apertures (not shown) which are aligned with the previously mentioned aperture 21 in base receptacle 11 whereby the upper end of vertical standard 7 of base assembly 1 may project therethrough.

As previously mentioned the entire tray assembly 10 is mounted on standard 7 for both revolvable and vertical adjustment. This is affected by providing a collar 57 of pliable material or of split form around standard 7 and, further, a clamp 59 around the collar 57, said clamp being opened and closed by a conventional wing nut and bolt combination 61. Thus, the position of the clamp determines the position of the table on the standard 7. Where the table is positioned so high on the standard that the top end thereof is below the horizontal member 55, this compartment may be used as a container for a boxed product such as, for example, hand tissues and the like.

In use the lower or base receptacle is designed primarily to receive hair curling rollers. These rollers vary in diameter from roughly an inch up to 2 inches or more. Since the bottom of the base receptacle is sloped the rollers may be readily stacked in the various compartments in such a manner that their central axis are disposed parallel to each other and to the longer side of the table. Thus, they are always available to the stylist in orderly form so that he or she may quickly select and or discard these items from and to the proper compartments.

The various compartments formed in the tiered tray are designed to receive clips, clamps, bobby pins and the like. Preferably the two larger compartments are filled with clamps since the sloping walls provide a means whereby the operator can retrieve or discard such clamps simply by feel and these walls will tend to direct the articles into the center of the specific compartment.

The smaller end compartments provide a place for smaller items such as hair pins, etc., all of which are disposed conveniently for use by the stylist.

Having described the invention in detail, what is claimed is:

1. A tray assembly comprising a generally rectangu-

lar base receptacle and a tiered tray disposed above said base receptacle, stand means for supporting said assembly, said base receptacle having a bottom comprised of a V-shape with the apex of the V disposed parallel to the longer dimension of said base receptacle, vertical side walls surrounding said bottom, a plurality of dividers disposed parallel to each other and to the shorter end dimension of said tray; said tiered tray being disposed above said base receptacle and having its long and short dimensions paralleling the longer and shorter dimensions of said base receptacle, the shorter dimension of said tiered tray being substantially less than the shorter dimension of said base receptacle to permit of manual access to the base receptacle; said tiered tray having a flat bottom and two inwardly sloping longer side walls and vertical end walls defined by integral extensions of the shorter end walls of said base receptacle; a pair of dividers symmetrically spaced from the central axis of the tiered tray; a second pair of dividers symmetrically spaced from said first pair of dividers and from the vertical end walls of the tiered tray, a plurality of parallel subdividers disposed between said end wall of said tiered tray and said spaced dividers to form multiple compartments adjacent said end walls; a pair of vertically aligned apertures formed in the V bottom of said base receptacle, and said horizontal bottom of said tiered tray; said stand means including a vertical standard passing upwardly through said apertures and means movable along said standard to selected positions and engageable with said tray assembly for adjustably positioning said tray assembly on said stand assembly.

2. A tray assembly as defined in claim 1 including a horizontal member disposed above the bottom of said tiered tray and having an aperture aligned vertically with the apertures in said base receptacle and the bottom of said tiered tray to receive the upper end of said vertical standard.

3. A tray assembly as defined in claim 1 wherein the shorter side of the tiered tray is less than half of the shorter dimension of said base receptacle and said sloping walls thereof are disposed at an acute angle to the V-shaped bottom of said base receptacle.

4. A tray assembly as defined in claim 1 wherein said tray assembly is formed of transportation plastic material.

5. A tray assembly as defined in claim 1 wherein said tray engaging means comprises a clamp surrounding the vertical standard of said base assembly.

6. A tray assembly as defined in claim 5 wherein said base assembly includes at least three outwardly extending legs and the ends of said legs are provided with caster wheels.
